PROCESS OF CRACKING OIL VAPORS INTO VAPOR PHASE

Filed Feb. 17, 1928.

UNITED STATES PATENT OFFICE

JOSEPH B. WEAVER AND CARY R. WAGNER, OF CHICAGO, ILLINOIS, ASSIGNORS TO THE
GYRO PROCESS COMPANY, OF DETROIT, MICHIGAN, A CORPORATION OF MICHIGAN

PROCESS OF CRACKING OIL VAPORS INTO VAPOR PHASE

Application filed February 17, 1928. Serial No. 255,142.

This invention relates to processes of converting high boiling hydrocarbons into hydrocarbons of low boiling point, and has particular reference to high temperature processes wherein the oil while undergoing conversion is maintained in the vapor phase by the heating thereof to temperatures usually in excess of 1000° Fah.

In the vapor phase method of converting oil the temperatures employed ordinarily are considerably higher than those which obtain in the so called liquid phase method. Also, the pressures maintained on the oil during conversion are considerably different in that the vapor phase methods utilize low pressures, which generally do not exceed thirty pounds per square inch, whereas the liquid phase methods employ pressures which are much higher and wherein pressures of several hundred pounds to the square inch are common. Further, there is a considerable difference in the combustion properties of the products produced by the two methods, particularly with respect to the motor fuel products or fractions thereof.

The motor fuel fractions produced by vapor phase methods are highly non-detonating when carburetted and burned in the cylinders of an internal combustion engine and, in fact, the anti-detonating value of such fractions is sufficiently high to permit the latter to be blended with fractions produced by liquid phase methods so that a composite fuel may be provided which possesses the requisite anti-knock value suitable for present day internal combustion motors. These attributes of a vapor phase motor fuel products, among others equally important and advantageous, are well recognized in the industry, but owing to difficulties in design and operations vapor phase methods of cracking hydrocarbons have not been widely used heretofore by the petroleum industry, liquid phase methods having been generally employed because of greater convenience in control and a more complete recovery of the products sought. It is, therefore, an object of the present invention to provide a vapor phase method of cracking oil and in effecting the separation and

refining of the several fractions thereof by the use of a system which may be safely and readily controlled and through the operation of which a motor fuel product is obtainable characterized by its stability, color, absence of gum forming compounds when the product is left standing, of improved anti-knock value, volatility and other properties hereinafter more fully explained.

The present invention is directed further to a vapor phase process of producing motor fuels, and other less valuable fractions, wherein the hydrocarbons during conversion, and while admixed with steam, are heated to reaction temperatures in excess of 1000° Fah., and wherein upon the completion of the conversion process reactions are sharply checked by suddenly and rapidly cooling the vapors to a sub-conversion temperature less than 600° Fah., and wherein the vapor present following the cooling operation is separated from the heavier products and passed through a bed of fuller's earth or other equivalent material for the purpose of filtering the vapors and minimizing the presence of objectionable compounds which tend to undesirably color the oil, produce gum forming compounds, reduce the volatility and anti-knock value of the motor fuel product and to detract in other ways from the essential value of the product.

More specifically, the present invention resides in a vapor phase process of oil conversion wherein steam and oil vapors present following conversion are passed through a body of fuller's earth contained in a closed tower for the purpose of removing objectionable compounds of polymers to produce a final product of improved value as a motor fuel, the use of the steam present in the oil vapor serving to facilitate and improve the operation and products resulting from the passing of the vapors through the filtering or contact material.

For a further understanding of the invention reference is to be had to the following description and the accompanying drawing, wherein:

The figure is a diagrammatic view of a

vapor phase cracking system designed to operate in accordance with the features of the present invention.

Referring more particularly to the drawing the numeral 1 designates a heater or converter which consists of a furnace setting divided internally by a bridge wall 2 so as to define burner and tube chambers. An oil or gas burner 3 is arranged within the burner chamber and is employed to heat the interior of the converter to the desired temperature. Arranged within the tube chamber of the converter is a coil 4, through which is circulated oil vapor admixed with steam. When entering the coil 4 the vapors may be at a temperature of 750° Fah., but this temperature is immediately raised to a point in excess of 1000° Fah. by exposure of the entrance portion of the coil to the radiant heat developed in the burner compartment of the converter. The oil vapors travel at high velocity, usually between 4000 to 8000 feet per minute through the coil 4 so that any given body of oil vapor will travel through the entire coil or converter in a period of time less than two seconds. Low pressures obtain on the oil while the latter is travelling through the converter, such pressures usually not exceeding 30 pounds per square inch. The coils 4 preferably contain a core of ferrous oxide, since experience has demonstrated that improved results are obtainable when this catalytic or contact material is employed in the several passes of the coil 4. It is during the rapid travel of the oil vapors through the coil 4 that the conversion reactions take place, the vapors leaving the coil at a temperature of approximately 1150° Fah. These conversion temperatures may vary in range between 1000° F. and 1250° F.

In the operation of this system it is necessary to instantly check the conversion reactions immediately upon discharge of the vapors from the converter unit 1. This is done in order to minimize the formation of non-condensable gases and the formation or liberation of free carbon, which tends to accumulate rapidly in the tubes or passages of a vapor phase process when the vapors are allowed to expand and cool slowly following the stage of conversion.

To effect this rapid cooling of the highly heated and reactive vapors leaving the converter, the discharge end of the coil 4 terminates in a restricted conduit 5 which enters a cooler 6. Also situated within the cooler 6 is a spray nozzle 7 through which is forced the cold charging stock which is supplied to the system by way of the pipe line 8. The charging stock issues from the nozzle 7 in the form of a finely divided mist of cold liquid particles and is brought into intimate contact over an extended surface with the hot vapors discharged from the

converter. This mixture takes place initially within the restricted conduit 5 wherein the velocity of travel of the oil vapors is comparable with that which obtains in the coil 4. This intimate contact between the cold spray and the hot vapors results in an instantaneous lowering of the temperature of such vapors from a point in excess of 1000° Fah. to a sub-conversion temperature of below approximately 600° Fah. The oils thus cooled may vary in temperature from 450 to 600° F. At this latter temperature the vapors are no longer reactive with the result that carbon deposition is practically eliminated, as set forth in U. S. patent to Weaver Reissue Patent No. 17,681, dated May 27, 1930.

The high boiling compounds collect in liquid form in the bottom of the cooler and are drawn off by way of a pipe line 9 to a hot oil tank 10. The liquid which collects in the bottom of the cooler 6 comprises the heavier ends of the charging stock which enters by way of the pipe line 8 and also the liquefied portion of the vapors which have issued from the converter 1. These liquefied fractions are then pumped by way of the pipe line 11 to a preheater 12 wherein the temperature of the charging stock is raised from approximately 400° Fah. to approximately 750° Fah. The temperature in the preheater, however, is such as to preclude any appreciable conversion on the part of the oil vapors. In the preheater 12 the oil is partially reduced to a state of vapor and at a temperature of roughly 750° Fah. the mixture of oil and vapor leaves the preheater and enters an evaporator 13. In advance of the evaporated superheated steam introduced by a line 14 is admixed with the oil and vapor and passes overhead with the vapor from the evaporator into the upper or first pass of the coil 4. The heavy bottoms which accumulates in the evaporator are removed from the system by way of a line 15 in the form of fuel oil. The steam and oil vapors then circulate through the converter wherein the conversion reactions take place as previously specified.

The lighter fractions of the charging stock which are heated and vaporized in the cooler 6 and the vaporized fractions of the cracked stock discharged from the converter, pass overhead from the cooler by way of the pipe line 16 and enter a fractionating column or tower 17. Within this tower there takes place, as usual, a separation of the hydrocarbon fractions of different boiling point, the heavier or higher boiling point fractions accumulating as a liquid in the bottom of said tower and are then led back to the hot oil tank for recirculation through the system by means of the pipe line 18. The lighter or unvaporized fractions pass overhead from the tower 17 and enter the upper part

of a clay tower 19. Arranged within this tower is a bed of filtering material, preferably fuller's earth, which is designated by the numeral 20. The steam laden oil vapors 5 penetrate through this body of material for the purpose of removing from the vapors objectionable properties which, if present, would diminish the value of the final product. In this respect we have found that the 10 presence of steam in the oil vapors when the latter are filtering through the fuller's earth results in greatly improving the final product and that the system operates to much better advantage than it does when the steam 15 is omitted. The filtering material, namely fuller's earth or its equivalent, removes highly colored compounds, eliminates the use of acid treatment and the necessity of re-running the distillates obtained, removes 20 gum forming compounds and produces a distillate of clear color. After filtering through the bed of fuller's earth the vapors are then passed to a second fractionating tower 21, the final vapors passing overhead 25 from this tower to a condenser 22 and then to a storage tank 23. The liquid which accumulates in the bottom of the second fractionating tower 21 is transferred to the hot oil tank by way of the pipe line 24, where 30 it may be recirculated through the system.

A typical test run made in accordance with the above described steps is given in the table immediately following:

Barrels gas oil charged	1168.8
Barrels motor fuel produced	654.6
Barrels fuel oil produced	206.1
Cubic feet dry gas produced	1,936.925
Gas consumed as fuel, cubic feet	756.672
Average temperature of cracking	1130° F.
Average temperature vapors ex arrester	580° F.
Temperature vapors to fuller's earth tower	304° F.
Temperature vapors ex fuller's earth	375° F.
Pressure on oil to arrester sprays	90 lbs.
Pressure on oil to economizer	25 lbs.
Pressure on evaporator	10.5 lbs.
Pressure at converter inlet	8 lbs.
Pressure at converter outlet	3.9 lbs.
Pressure entering fuller's earth tower	2.3 lbs.

The gas oil charged had an average A. P. 45 I. gravity of 39.6°, flash point of 235° F. and a fire point of 255° F. The motor fuel produced tested 59.7° gravity, initial 88, 20% @ 184, 50% @ 248, 90% @ 372 and end point 421. The color of the finished 50 product was +20 Saybolt.

We are aware of the fact that it has been proposed heretofore to pass hydrocarbons in a state of vapor through a filtering material, such as fuller's earth, for the purpose 55 of removing objectionable unsaturated compounds in certain desired motor fuel products. Prior to our invention, however, we are not aware of any analogous system employing the principle of mixing steam with the oil vapors to procure greater efficiency on the part of the filtering operation wherein fuller's earth is employed. Typical of 60 many tests made to determine the comparative merits of such systems operating with

and without the use of steam are the results shown in the following table:

Amount	No steam	With steam	
Amount treated	3000 c. c.	3000 c. c.	70
End point of charge	416° Fah.	415° Fah.	
Amount fuller's earth used	1.25 lb.	1.25 lb.	
Loss during fuller's earth treatment	5.3%	2.0%	
Polymers in product recovered (loss as bottoms on rerunning)	4.8%	1.25%	
Temperature of cut on rerun	420° Fah.	422° Fah.	
Amount gasoline recovered	89.8%	94.5%	75
Losses not accounted for	0.1%	2.25%	
Iodine No. of charge	207.9	208.0	
Iodine No. of treated gasoline	198.4	202.0	
Unsaturates in charge	48.2	48.0	
Unsaturates in finished gasoline	47.7	53.2	
Gravity of charge, ° A. P. I.	50.7	50.7	
Gravity of finished gasoline, ° A. P. I.	51.8	50.8	

The above table represents merely average conditions and discloses that with the use of steam loss of the charging stock was reduced by 3.3%; reduction in polymers in recovered product 3.55%; a gain of 4.7 in 85 the total amount of gasoline recovered; an increase of 4.5% in the unsaturated compounds present in the finished gasoline. At this point it might be stated that the process

does not aim to minimize or eliminate the presence of unsaturated compounds, as in previous processes, but operates to retain a greater percent of the unsaturated compounds which are not objectionable in the finished product. These objectionable compounds constitute but a small fraction of the total unsaturates present, the undesired proportions tending to discolor the oil and to produce the gum forming compounds. 90

These, however, are effectively removed by the aid of fuller's earth with the steam present. It will be understood that it is desirable to retain in the final product a high content in unsaturated compounds, 95 since these unsaturates possess or impart to the fuel a high anti-knock value. The motor fuel distillate upon standing does not reproduce gum forming constituents nor does it lose its color. The fuller's earth thus serves the double purpose of removing through polymerization the undesired constituents and at the same time stabilizes its color without any additional treatment.

It will thus be observed that in carrying 110 out the invention a mixture of gasoline and steam, together with fixed gases, is passed through the fuller's earth bed wherein the latter is maintained at a temperature materially below the boiling point of the heaviest hydrocarbons present. At this time the diolefines and gum forming compounds present in the mixture are converted into heavy hydrocarbons which can be readily removed by fractional distillation. Also, some of the normally gaseous olefines are converted 115 into valuable gasoline fractions and the desirable aromatic content is very appreciably increased. The steam present serves the purpose of lowering the temperature of the 120

125 130

exothermic polymerization reactions so that desirable olefines are not destroyed and provides for better regulation of the polymerization reaction temperatures and conditions.

5 What is claimed is:

The method of treating cracked low boiling petroleum oils containing high percentages of unsaturated compounds to remove therefrom only excessive undesirable 10 unsaturated compounds which produce gums and discoloration on standing, the steps which comprise: introducing vapors of such cracked oils admixed with steam into a confined polymerizing zone, bringing the 15 mixture of oil and water vapor during the passage thereof through said zone into intimate contact with a finely divided solid adsorbent catalyst, the steam being present in such proportion as to cause polymerization 20 of approximately one-fourth of the total unsaturates which would be polymerized without the presence of steam, the remaining unsaturates being unpolymerized and thus present in desirable increased amount 25 over that originally present in the oil vapors charged to the polymerizing zone, removing the material from the polymerizing zone, and separating the treated oil as vapors from the high boiling oils produced in the 30 polymerizing zone and containing the aforesaid undesirable compounds.

In testimony whereof we affix our signatures.
